UNITED STATES PATENT OFFICE.

OSCAR W. FAUSER, OF BELLEROSE, NEW YORK, ASSIGNOR TO CONGOLEUM-NAIRN, INC., A CORPORATION OF NEW YORK.

DESIGN FOR A RUG OR SIMILAR ARTICLE.

Application filed October 29, 1927. Serial No. 23,938. Term of patent 7 years.

To all whom it may concern:

Be it known that I, OSCAR W. FAUSER, a citizen of the United States, residing at 44 Hudson Road, Bellerose, in the county of Nassau and State of New York, have invented a certain new, original, and ornamental Design for Rug or Similar Article (Case #32), of which the following is a specification, reference being had to the accompanying drawing, forming a part hereof.

The figure is a plan view of one-fourth of the rug showing my design, it being understood that the design of the representative illustration is repeated in the other three-fourths of the rug.

I claim:

The ornamental design for a rug or similar article, substantially as shown and described.

In testimony whereof, I affix my signature.

OSCAR W. FAUSER.
